E. SANDOW.
PHYSICAL EXERCISER.
APPLICATION FILED JULY 7, 1915.

1,194,884.

Patented Aug. 15, 1916.

UNITED STATES PATENT OFFICE.

EUGEN SANDOW, OF LONDON, ENGLAND.

PHYSICAL EXERCISER.

1,194,884.

Specification of Letters Patent. Patented Aug. 15, 1916.

Application filed July 7, 1915. Serial No. 38,459.

To all whom it may concern:

Be it known that I, EUGEN SANDOW, a subject of His Majesty the King of Great Britain, and a resident of London, England, have invented a new and useful Improved Physical Exerciser, of which the following is a specification.

This invention relates to physical exercisers and consists in a form of same which is, or may be combined, or used, with a doll or figure whereby a child playing with same may be caused unconsciously to take physical exercise.

In my United States Patent of the 5th January, 1915, No. 1,123,570, there is described a device consisting of a doll or figure having a physical exercising device forming a part of same as the limbs of the doll or figure or some of them.

According to the present invention, however, instead of rendering the limbs of the doll or figure extensible it is proposed to obtain the same result by applying external extensible (by which is meant also retractile or elastic) parts or members to the doll or figure by providing a jacket, trousers, or other garment, equipment, harness, or the like, adapted to fit an ordinary doll or figure, said garment, equipment, or the like, having the physical exercising means combined therewith, the exercising means consisting, for example, of extensible sleeves or limb portions to the garments or extensible parts carried by the garment, or other devices applied outside of the doll or figure as the limbs of a garment or equipment in which latter term is included a harness or other covering for the body of a doll or figure.

It will be understood that a garment or the like constructed as above described is intended to be fitted upon a doll or figure and the latter employed as an exerciser in the manner described in the aforesaid specification, thus forming a ready means of turning an ordinary doll or play figure into a useful and beneficial unconscious exercising medium for a child.

Some constructions of garments and devices are illustrated in the accompanying drawing as embodiments of the invention by way of example.

In this drawing:—Figure 1 shows a jacket and trousers carried on the figure of a doll: Fig. 2 shows a portion of a jacket only in a modified form: Fig. 3 is a view of the in-

side of a part of a jacket to show another modification: Fig. 4 is a view of a belt attachment: Fig. 5 is a view of a harness: and Fig. 6 is a view of a piece of elastic 60 fabric.

In Fig. 1 the exerciser comprises a jacket 1 having arms consisting of coiled springs 2 attached inside the sleeves by sewing them to the fabric of the sleeves at the points 3, 4, of the shoulders and wrists, respectively. The material of said sleeves is either knitted or is so loose, elastic, or full, or is formed in such a manner as to allow the sleeves to stretch with the springs when the latter are 73 pulled. The sleeves in the form shown are longer than the arms A of the figure so that the latter are not in the way of the ends of the sleeves which have to be gripped by the child when extending the arms though they 75 may be shorter. To afford a convenient grip in the form shown the sleeve ends are contracted by puckering them as at 5. To strengthen the jacket at the point of insertion of the sleeves a strap 6 may be sewn at 80 the back inside, as indicated at 6^a, up to the shoulder points, the front portion being left loose so that it may be strapped upon the chest of the doll before the jacket is buttoned up.

The trousers are formed in the same way, of loose, elastic or full material with the coil springs 7 inside of same secured at 8 by stitching to the fabric, and secured at the lower ends by attachment as at 9^a by stapling 90 to the upper parts of wooden feet 9 serving as grips for the hands in place of the grips formed by the puckering 5 on the arms, the trouser legs being longer than the ordinary legs B of the figure, though they may be 95 shorter if the wooden feet are absent.

Fig. 4 shows a belt 10 provided with a buckle 10^a which can be placed under the arms of the figure as seen in Fig. 1 and which is also provided with a hook 11 to enable the figure to be hung to a ring or hook in a wall or the like so that the pull upon the sleeve and trouser parts may be effected against a fixed point.

Fig. 2 shows a jacket 12 simulating a gymnastic coat or jacket in which the upper end of a coil spring 22 is secured to the inside of the sleeve as at 13 by stitching and the lower end is secured to a ring 14 carrying a spring grip dumb bell 15, the usual hands of the 110 doll being concealed by the sleeve.

Fig. 3 shows a loose elastic cord 16 hooked

at 17 to an eyeleted tab 18 stitched at 18^a inside a jacket 19 said cord passing down the sleeve so that it is concealed in same, and terminating in a hand 20.

5 Fig. 5 shows a harness for a doll or figure which is preferably applied outside the clothes. It consists of strap 24 which may be placed around the neck of the doll so as to rest on the shoulders and a waist strap 25 both having buckles 24^a and 25^a respectively, for tightening same, the two belts being connected by straps 26.

The neck strap 24 has tabs 27, 27, preferably of leather attached to same and through holes in these are passed the ends of members consisting of elastic cords 28, 28, which ends are bent over and secured at 28^a, the other ends being similarly passed through and secured to eyelets 29, 29, of grip dumb bells 30, 30. The waist strap 25 has similar tabs 31 to which are attached at 33 members consisting of elastic cords 32 the other ends of which are attached to looped straps 34, 34, through which the foot may be passed such straps having pieces 35 to hold the instep and prevent the foot from being pushed through too far. The members 28 and 32 thus represent the respective limp portions of a garment or garments.

30 A doll or figure carrying this form of harness may be attached to the wall by a belt such as that shown in Fig. 4 while the child can exercise both its feet and arms by means of the members 32 and 28 or either 35 of same.

In place of having coiled springs attached inside the fabric of the sleeves or trouser portions of a doll's clothing such sleeves or trouser portions may be made of a suitable 40 elastic fabric such as shown in Fig. 6 where

the longitudinally arranged threads 36 are of rubber and the cross threads 37 of stout yarn, a fabric being thus provided which may be made up in the usual way into a sleeve or other tubular part which can form 45 part of a garment and be gripped and extended by a child.

As many changes could be made in the above constructions and also many apparently widely different embodiments of the 50 inventions be devised without departing from the scope of same it is intended that all matter contained in the above description or shown in the accompanying drawings shall be interpreted as illustrative and 55 not in a limiting sense.

What I claim is:—

1. A physical exerciser comprising a garment for a doll or figure and an extensible limp portion to such garment. 60
2. A physical exerciser comprising a garment for a doll or figure and extensible means applied to a limb portion of such garment.
3. A physical exerciser comprising a garment for a doll or figure and an extensible device concealed within a limb portion of same. 65
4. A physical exerciser comprising means adapted to be fitted over a doll or figure and 70 including an extensible member.
5. A physical exerciser comprising a garment for a doll or figure and a tubular part carried by said garment adapted to cover a limb of the doll or figure and means carried by such tubular part to render same extensible. 75

In testimony whereof I have hereunto set my hand.

EUGEN SANDOW.
